UNITED STATES PATENT OFFICE.

EUGÈNE SCHNEIDER, OF PARIS, FRANCE, ASSIGNOR TO SCHNEIDER & CIE., OF PARIS, FRANCE, A JOINT-STOCK COMPANY OF FRANCE.

APPARATUS FOR REPEATING AUTOMATICALLY ON A RAILWAY-LOCOMOTIVE, TRACK SIGNALS PROVIDED FOR THE PROTECTION OF MOVING TRAINS.

1,352,389.

Specification of Letters Patent. Patented Sept. 7, 1920.

Application filed February 28, 1920. Serial No. 362,121.

To all whom it may concern:

Be it known that I, EUGÈNE SCHNEIDER, a citizen of the Republic of France, and a resident of Paris, France, have invented 5 new and useful Improvements in Apparatus for Repeating Automatically on a Railway-Loconotive, Track-Signals Provided for the Protection of Moving Trains, which invention is fully set forth in the following specification.

10 This invention has for its object to provide an improved apparatus for repeating on a railway locomotive, track signals provided for the protection of moving trains.

15 The principal devices hitherto proposed for this purpose are either purely mechanical or electro mechanical.

20 The mechanical devices comprise hangers pivoted to the locomotive and designed to be actuated by the passage of the latter over depressible inclined planes connected to the track signals. These devices necessitate an installation projecting inside the standard 25 clearance gauge of the railway and are thus exposed to rapid damage.

25 The systems employing electricity as the agent for establishing the connection between the locomotive and the track signals, have the drawback that they comprise, as 30 essential parts, a metallic contact whose drawbacks are well known. Where the lines of magnetic force are utilized, the resulting effects are very small, and have therefore to be intensified by amplifiers of electric or 35 mechanical nature, which are complex and costly devices subject to numerous stoppages in their working.

40 The same drawbacks attend also apparatus based on transmission by means of Hertzian waves.

45 The improved apparatus is altogether more simple in construction and more reliable in operation than the devices hitherto known.

50 The improved apparatus consists essentially of a simple air ejector, such as a blower or ejector proper operated by steam taken from the locomotive boiler, and arranged at any suitable point under the locomotive. This ejector is designed to create in the neck of a converging-diverging nozzle, a constant depression of the air pressure for a given steam pressure. The diverging portion of the nozzle is arranged in such a man-

ner that its mouth passes during the passage of the train, sufficiently close to screens or dampers that are connected mechanically to the track signals, thereby modifying the discharge of the mixture of air and steam from the nozzle, according to the positions which 60 they receive and which correspond to the positions given to the signals.

These modifications in the discharge of the mixture from the nozzle, produced automatically by the setting of the signals, result in producing variations in the depression of the air pressure in certain regions of the nozzle, more particularly near the neck, which variations can be repeated upon a diaphragm, by the hand of an indicating apparatus and by the stylus of a recording apparatus.

55 The movements of the diaphragm may be used for controlling the operation of an acoustic signal, such as a whistle. Similarly, the movements of a hand influenced by the variations of the depression of the air pressure, over a dial, may be utilized to cause a visible signal to appear or disappear. Moreover, a cock or a valve may be 60 operated for producing a discharge or an admission of air, acting upon the continuous compressed air or vacuum brake of the train.

65 In the accompanying drawings which illustrate by way of example a practical form of this invention:—

70 Figure 1 is a sectional elevation taken along the axis of the converging-diverging device installed under the locomotive. This figure shows in cross section one of the screens connected mechanically to a track signal opposite the mouth of the nozzle.

75 Fig. 2 is a partial plan showing the said screen and its connection to the corresponding signal.

80 Fig. 3 is a cross section drawn to a larger scale on the line III—III of Fig. 1.

85 Fig. 4 is a cross section on the line IV—IV of Fig. 3.

90 Fig. 5 is a vertical section drawn to a larger scale than that of Fig. 1, of a valve distributor connected to the diaphragm affected by the variations of the depression in the nozzle, and designed to operate a compressed air whistle.

100 Fig. 6 is a sectional elevation of the signal-indicating mechanism.

Under the locomotive there is arranged transversely a nozzle A—B supported for instance by one of the longitudinals D of the locomotive frame. This nozzle comprises a 5 converging element A the entry of air into which takes place through a flaring inlet *a* and which is connected to a diverging element B, whence the air is discharged through a mouth *b*, opening inside the 10 standard clearance gage (indicated by dot and dash lines G) and within the vertical plane G¹ that limits the said gage.

A constant depression of the air pressure is maintained in the neck of the nozzle A—B 15 during the travel of the train. For this purpose a steam ejector C is arranged in the nozzle, in front of the diverging member B¹ of a device A¹—B¹ for multiplying the depression of known construction.

- 20 The ejector is supplied with steam from the locomotive boiler, this steam being conveyed by a pipe E to the annular passage *c*. The steam jets *c*¹ of any desired number, suck the air that has entered at *a*, and produce in the neck of the converging-diverging device A²—B² of the depression-multiplier, a depression, which remains constant so long as the amount of air discharged through the mouth *b* remains constant.
- 30 But on the said mouth *b* passing past a screen which obstructs more or less the discharge of the said air, the depression will be reduced, and the reductions in the depression which have been rendered very sensitive 35 by the depression-multiplier A¹—B¹—A²—B², are received and recorded by the apparatus carried on the locomotive. The depression-multiplier which in this example is arranged in the nozzle back of the ejector C 40 may be situated elsewhere, for instance in the nozzle in front of the ejector, when it is desired to utilize the sudden variations of the depression that are produced in this region under certain conditions.
- 45 The receiving and recording apparatus may of course vary as desired.

For instance, the neck of the converging-diverging device A²—B² may be connected by a pipe F to a pocket H closed by a 50 flexible diaphragm I. Any variation of the depression in the pocket H will cause a movement of the diaphragm I. This movement can be transmitted by a rod J to a compressed air distributor for operating a 55 whistle.

In the example shown, Figs. 5 and 6, this distributor comprises a box K connected by a pipe K¹ to the compressed air reservoir on the locomotive, and by a pipe K² to the 60 whistle. A valve L pressed by a spring against a seat *k* in the box K, shuts off normally the communication between K¹ and K². On the rod J there is mounted a pilot-slide valve J¹ pierced with a bent duct J² 65 and adapted to slide in the main valve L.

Normally, that is to say, when the constant depression created by the ejector C, exists in the pocket H, the rod J and the slide valve J¹ carried by the latter, occupy the position shown in Fig. 5. The main valve L bears against its seat; the compressed air, of reservoir pressure, passes around the main valve and also inside the latter through the narrow gap *l*. Communication between K¹ and K² is shut off by 70 the slide valve J¹.

As soon as the diaphragm I is raised by reason of a diminution in the depression in the pocket H, the slide valve J¹ is moved into a position in which it establishes communication between the inside of the main valve and the pipe K². The result is a sudden diminution of pressure inside the main valve, and consequently a lifting of the latter. This lifting of the main valve allows compressed air to pass from K¹ to K², and consequently operates the whistle to give the alarm.

The pocket H, Fig. 6, may be connected by a branch pipe m to a vacuum gage M 80 whose hand M¹ may carry an indicating disk m¹.

The same pipe m or another pipe, may connect the pocket H to a bellows N for operating the stylus n of a recording apparatus of any suitable type.

The screens connected to the track signals may be constituted for instance as shown in Figs. 1 and 2:—

In a box O fixed to the rail chair P, 100 there are mounted rotatable vertical axle-pins q carrying shutters Q. The connection of all the axle pins q to the respective track signal may be effected by means of forked levers q¹ between the prongs of which there 105 extends and is jointed a common rod R connected to the track signal.

The sheet metal shutters Q may be moved into a position parallel to the track by the setting of the signal at danger; they are 110 thus situated a few centimeters away from the mouth *b* when the latter is moving past the screen.

The operation of the indicating and recording devices may be started at the passage of each signal even when the latter is at line clear. For this purpose it is merely necessary that the normal position of the screen to be actuated, is suitably chosen in such a manner as to offer a partial obstacle 115 to the discharge of the air from the mouth *b* of the nozzle A—B.

It is to be understood that by variously adjusting the screens controlled by the various signals (distant signals, home signals 125 or stopping signals, etc.), it is possible to produce different warning or indicating and recording effects.

What I claim is:

1. An apparatus for automatically repeat- 130

- ing upon the locomotive track signals for protecting moving trains, characterized by an air suction or ejecting device arranged under the locomotive for creating in a duct 5 connected to acoustic optical or other warning devices, and to a recording device, a constant depression of the air pressure during the motion of the train, said air suction or ejecting apparatus being combined with 10 pivoting screens connected to the track signals and so arranged as to present in front of the air outlet of the said air suction or ejecting device carried by the locomotive, an obstacle to the normal outflow of the air 15 in such a manner as to modify the depression that is normally maintained in the said duct connected to the warning and recording devices.
2. An apparatus as claimed in claim 1, 20 wherein the air-duct comprises a converging-diverging nozzle arranged under the locomotive transversely of the longitudinal axial plane of the latter, in which there is arranged in front of an air pressure depression-multiplier, an air-ejecting device supplied with steam from the locomotive boiler; the neck of the inner converging-diverging member of the depression-multiplier being connected by a pipe to a pocket closed by a 25 diaphragm which is in turn connected by a rod to a pilot slide valve sliding in a main valve that normally shuts off the communication between a whistle and the compressed air reservoir of the locomotive.
3. In a railway signal, a nozzle mounted 30 on a car to form an air-duct, means for normally maintaining a depression of the air pressure in the nozzle, signal-indicating means communicating with the nozzle to be 35 actuated by a fluctuation of the depression therein, and a screen mounted adjacent to the track to register with the mouth of a passing nozzle to cause a fluctuation of the depression in the nozzle.
4. In a railway signal, a nozzle mounted 40 on a car to form an air-duct, an ejector in the nozzle for normally maintaining a depression of the air pressure therein, signal-indicating means communicating with the 45 nozzle to be actuated by a fluctuation of the depression therein, and a screen mounted adjacent to the track to register with the mouth of a passing nozzle to cause a fluctuation of the depression in the nozzle.
5. In a railway signal, a nozzle mounted 50 on a car to form an air-duct, means for normally maintaining a depression of the air pressure in the nozzle, an amplifier in the nozzle to augment the depression therein, 55 signal-indicating means communicating with the amplifier to be actuated by a fluctuation of the depression therein, and a screen mounted adjacent to the track to register with the mouth of a passing nozzle to cause a fluctuation of the depression in the nozzle.
6. In a railway signal, a nozzle mounted 60 on a car to form an air-duct, an ejector in the nozzle directed toward the mouth thereof for normally maintaining a depression of the air pressure in the nozzle, an amplifier in the nozzle between the intake end thereof and the ejector to augment the depression maintained by the ejector, signal-indicating means communicating with the amplifier to be actuated by a fluctuation of the depression therein, and a screen mounted adjacent to the track to register with the mouth of a passing nozzle to cause a fluctuation of the depression in the nozzle 65 and in the amplifier.
7. In a railway signal, a nozzle mounted on a car comprising converging and diverging members joined together to form an air-duct with a constriction at the juncture 70 of said members, means for forcing air outwardly through the diverging member to maintain a depression of the air pressure in the converging member, signal-indicating means communicating with the converging 75 member to be actuated by a fluctuation of the depression therein, and a screen mounted adjacent to the track to register with the mouth of a passing nozzle to cause a fluctuation of the depression in the nozzle 80 and in the amplifier.
8. In a railway signal, a nozzle mounted on a car comprising converging and diverging members joined together to form an air-duct with a constriction at the juncture 85 of said members, means for forcing air outwardly through the diverging member to maintain a depression of the air pressure in the converging member, signal-indicating means communicating with the converging 90 member to be actuated by a fluctuation of the depression therein, and a screen mounted adjacent to the track to register with the mouth of a passing nozzle to cause a fluctuation of the depression in the converging member.
9. In a railway signal, a nozzle mounted on a car comprising converging and diverging members joined together to form an air-duct with a constriction at the juncture 95 of said members, an ejector located in the nozzle at the constricted part of the air-duct for forcing air through the diverging member to maintain a depression of the air pressure in the converging member, signal-indicating means communicating with the converging member to be actuated by a fluctuation of the depression therein, and a screen mounted adjacent to the track to register with the mouth of the diverging member of a passing nozzle to cause a fluctuation of the depression in the converging member.
10. In a railway signal, a nozzle mounted 100 on a car comprising converging and diverging members joined together to form an air-duct with a constriction at the juncture of said members, an ejector located in the nozzle at the constricted part of the air-duct for forcing air through the diverging member to maintain a depression of the air pressure in the converging member, signal-indicating means communicating with the converging member to be actuated by a fluctuation of the depression therein, and a screen mounted adjacent to the track to register with the mouth of the diverging member of a passing nozzle to cause a fluctuation of the depression in the converging member.
11. In a railway signal, a nozzle mounted 105 on a car comprising converging and diverging members joined together to form an air-duct with a constriction at the juncture of said members, means for forcing air outwardly through the diverging member to maintain a depression of the air pressure in the converging member, an amplifier in the converging member to augment the depression therein, signal-indicating means communicating with the amplifier to be actuated by a fluctuation of the depression therein, and a screen mounted adjacent to the track to register with the mouth of the diverging member of a passing nozzle to cause a fluctuation of the depression in the converging member.
12. In a railway signal, a nozzle mounted 110 on a car comprising converging and diverging members joined together to form an air-duct with a constriction at the juncture of said members, means for forcing air outwardly through the diverging member to maintain a depression of the air pressure in the converging member, an amplifier in the converging member to augment the depression therein, signal-indicating means communicating with the amplifier to be actuated by a fluctuation of the depression therein, and a screen mounted adjacent to the track to register with the mouth of the diverging member of a passing nozzle to cause a fluctuation of the depression in the converging member.
13. In a railway signal, a nozzle mounted 115 on a car comprising converging and diverging members joined together to form an air-duct with a constriction at the juncture of said members, means for forcing air outwardly through the diverging member to maintain a depression of the air pressure in the converging member, an amplifier in the converging member to augment the depression therein, signal-indicating means communicating with the amplifier to be actuated by a fluctuation of the depression therein, and a screen mounted adjacent to the track to register with the mouth of the diverging member of a passing nozzle to cause a fluctuation of the depression in the converging member.

cause a fluctuation of the depression in the converging member and the amplifier.

10. In a railway signal, a nozzle mounted on a car comprising converging and diverging members joined together to form an air-duct with a constriction at the juncture of said members, an ejector located in the nozzle at the constricted part of the air-duct to force air outwardly through the diverging member to maintain a depression of the air pressure in the converging member, an amplifier in the converging member to augment the depression therein, signal-indicating means communicating with the amplifier to be actuated by a fluctuation of the depression therein, and a screen mounted adjacent to the track to register with the mouth of the diverging member of a passing nozzle to cause a fluctuation of the depression in the converging member and the amplifier.

11. In a railway signal, a nozzle mounted on a car to form an air-duct, means for normally maintaining a depression in the nozzle, signal-indicating means communicating with the nozzle to be actuated by a fluctuation of the depression of the air pressure therein, a screen having a variable surface mounted adjacent to the track to register with the mouth of a passing nozzle to cause a fluctuation of the depression in the nozzle, and means for varying the surface of the screen to modify the fluctuations of the depression in the nozzle to affect the actuation of the signal-indicating means.

12. In a railway signal, a nozzle mounted on a car to form an air-duct, means for nor-

mally maintaining a depression of the air pressure in the nozzle, signal-indicating means communicating with the nozzle to be actuated by a fluctuation of the depression therein, a screen mounted adjacent to the track to register with the mouth of a passing nozzle to cause a fluctuation of the depression in the nozzle, said screen comprising a plurality of movable members, and means for adjusting the movable members to vary the surface of the screen to modify the fluctuations of the depression in the nozzle to affect the actuation of the signal-indicating means.

13. In a railway signal, a nozzle mounted on a car to form an air-duct, means for normally maintaining a depression of the air pressure in the nozzle, signal-indicating means communicating with the nozzle to be actuated by a fluctuation of the depression therein, a screen mounted adjacent to the track to register with the mouth of a passing nozzle to cause a fluctuation of the depression in the nozzle, said screen comprising a plurality of pivoted shutters, and common means for turning said shutters to vary the surface of the screen to modify the fluctuation of the depression in the nozzle to affect the actuation of the signal-indicating means.

In testimony whereof I have signed this specification.

EUGÈNE SCHNEIDER.
